[57] CLAIM

The ornamental design for a front face of a steering wheel for vehicle, as shown and described.

DESCRIPTION

FIG. 1 is a front view of a front face of a steering wheel for vehicle according to our novel design; and,

FIG. 2 is a perspective view from the front right of a front face of a steering wheel for vehicle according to our novel design.

The broken lines included depict environment and are not part of the claimed design.
